UNITED STATES PATENT OFFICE.

JOHN C. BUSCHE, OF TURTLECREEK, PENNSYLVANIA.

VARIABLE-SPEED AND REVERSING GEAR.

SPECIFICATION forming part of Letters Patent No. 767,866, dated August 16, 1904.

Application filed April 19, 1904. Serial No. 203,867. (No model.)

To all whom it may concern:

Be it known that I, JOHN C. BUSCHE, a citizen of the United States, and a resident of Turtlecreek, in the county of Allegheny and 5 State of Pennsylvania, have invented a new and Improved Variable-Speed and Reversing Gear, of which the following is a full, clear, and exact description.

The invention relates to the transmission of 10 power from a driving member to a part to be driven; and its object is to provide a new and improved variable-speed and reversing gear arranged to permit convenient reversing of the motion and varying of the speed in both 15 forward and backward positions of the gear without requiring stopping of the driving member.

The invention consists of novel features and 20 parts and combinations of the same, as will be more fully described hereinafter and then pointed out in the claims.

A practical embodiment of the invention is represented in the accompanying drawings, forming a part of this specification, in which 25 similar characters of reference indicate corresponding parts in all the views.

Figure 1 is a side elevation of the improvement. Fig. 2 is a plan view of the same. Fig. 3 is an enlarged sectional side elevation of the 30 pinion, showing its teeth in a withdrawn inactive position. Fig. 4 is a like view of the same, showing the teeth in a projected active position. Fig. 5 is a perspective view of one of the pinion-teeth. Fig. 6 is a side elevation 35 of the movable hub of the pinion. Fig. 7 is a cross-section of the same on the line 7-7 of Fig. 6. Fig. 8 is a sectional side elevation of part of the face-wheel. Fig. 9 is an enlarged plan view of one of the split rings for fastening 40 a tooth of the face-wheel in place, and Fig. 10 is a plan view of part of the web or body of the pinion.

The shafts A and B, either of which may be driven, are journaled in a suitable frame C, 45 and on the end of the shaft A is secured a face-wheel D, and a pinion E is mounted to slide on and to turn with the shaft B. The face-wheel D is provided on its face with concentric rows of teeth D', D², D³, and D⁴, each pref- 50 erably formed by spaced equidistant pins re-

movably secured to the web of the wheel D and held in place thereon by split rings D⁵, (see Figs. 1, 8, and 9,) engaging annular grooves in the teeth and abutting against the under side of the web of the wheel D, as plainly 55 indicated in Fig. 8.

The pinion E consists, essentially, of a hub E', mounted to turn with and to slide lengthwise on the shaft B, a web or body E², and teeth E³, mounted to slide radially in suitable guideways in the web E² to permit of projecting the teeth beyond the peripheral face of the web E², (see Figs. 1 and 4,) so as to move the teeth E³ in mesh with the teeth of any one of the concentric rows D', D², D³, or 65 D⁴. The teeth E³ are adapted to be withdrawn within the body E² (see Fig. 3) to move the teeth out of mesh with the corresponding teeth D', D², D³, or D⁴ to allow convenient shifting 70 of the pinion E on its shaft B across the face of the face-wheel D preliminary to varying the speed or reversing the motion, as herein-after more fully explained.

In order to move the teeth E³ radially in or out, as above mentioned, the hub E' is provided with an annular groove having beveled parallel side walls E⁴ and E⁵ engaging correspondingly-beveled sides of a tongue E⁶ on the lower or inner end of each tooth E³, so that when the teeth E³ are in a withdrawn position, as shown in Fig. 3, and the body E² is held against lengthwise movement and the hub E' is moved lengthwise on the shaft B from the left to the right then the beveled side wall E⁴ acts on the tongue E⁶ to slide the teeth 85 E³ radially outward in their guideways in the web E² to protect the teeth E³ beyond the peripheral face of the web E², as illustrated in Fig. 4. When it is desired to withdraw the teeth E³, then the motion of the hub E' is 90 reversed—that is, it is moved from the right to the left—so that the beveled side wall E⁵ acts on the several tongues E⁶ to push the teeth E³ inward into a withdrawn position, as illustrated in Fig. 3.

In order to engage the beveled side wall E⁵ with the tongues E⁶, the said side wall is somewhat larger in diameter than the side wall E⁴ to readily engage the innermost ends of the tongues E⁶. When the teeth E³ are in a with- 100

drawn position, as shown in Fig. 3, then the pinion E can be bodily shifted lengthwise on the shaft B to bring the pinion in register with any one of the rows of teeth D', D², D³, or D⁴ on either side of the axis of the wheel D, it being understood that the shaft B extends diametrically across the face, as shown in Fig. 2, and the peripheral face of the web E² is immediately above the terminals of the teeth D', D², D³, and D⁴.

In order to allow of shifting the pinion E bodily on the shaft B, as described, the following device is provided: In the web E² is arranged an annular groove E⁷, engaged by 15 a shifting fork F, integral with a sleeve F', mounted to slide lengthwise on a bar G, attached to the frame C and extending above the shaft B parallel therewith and in the same vertical plane. In the bar G are formed sets 20 of notches G' and G², adapted to be engaged by a locking-pin H, mounted to slide in the sleeve F' and under the control of the operator manipulating a lever H', fulcrumed on the sleeve and connected with the locking-pin 25 H. By the operator pressing the lever H' against the tension of a spring H² the pin H is withdrawn from a notch G' to allow the operator to shift the sleeve F' lengthwise on the bar G, so that the shifting fork F carries the 30 pinion E along until the pinion stands in register with the corresponding row of teeth D', D², D³, or D⁴ on the desired side of the axis of the wheel D, and then the operator releases the lever H', so that the pin H engages the 35 corresponding notch in the set of notches G' or G² to hold the shifting fork F, and consequently, the pinion E, against lengthwise movement.

In order to shift the hub E' relative to the 40 web E², as previously explained, the outer end of the said hub is provided with an annular groove E⁸, engaged by a shifting lever I, fulcrumed on the sleeve F' and under the control of the operator, the shifting lever I 45 having a hand-lever I' for locking the lever I on a notched segment I², carried by the sleeve F'.

When the teeth E³ are projected and in mesh with one of the concentric rows of teeth D', D², D³, and D⁴ and it is desired to shift the 50 pinion E, then the operator first manipulates the lever I to impart a sliding motion to the hub E' for moving the teeth E³ into a withdrawn position, as above described and shown in Fig. 3, the hub E' then being locked against 55 lengthwise movement relative to the web E² by the hand-lever I' engaging the corresponding notch in the segment I². The operator now presses the lever H' to withdraw the locking-pin H from the corresponding notch in 60 the set of notches G' or G², and then the operator pushes the sleeve F' lengthwise on the bar G to move the pinion E lengthwise on its shaft B until the pinion stands in register with the desired row of teeth D', D², D³, or 65 D⁴ and on the desired side of the axis of the

wheel D. When the desired position has been reached, the operator releases the lever H', thus engaging the pin H with the corresponding notch in the set of notches G' or G² to hold the sleeve F', and consequently the web 70 E² and its teeth E³, against lengthwise movement. The operator now swings the lever I back to the former position, so as to project the teeth E³ beyond the peripheral face of the web E² to move the teeth in mesh with the 75 corresponding row of teeth D', D², D³, or D⁴.

It is understood that when the shaft A is the driving-shaft and the pinion E is in mesh with the row of teeth D'—say from the right-hand side of the axis of the wheel D, as shown 80 in Figs. 1 and 2—then a rotary motion is transmitted by the wheel D and pinion E to the shaft B at a high rate of speed, the shaft turning in a forward direction. When the pinion E is shifted from the right to the left in mesh 85 with any one of the rows of teeth D², D³, or D⁴ on the right-hand side of the axis of the wheel D, then the shaft B is still rotated in the same forward direction, but at a correspondingly-lower rate of speed; but when the 90 pinion E is shifted to the left of the axis of the wheel D in mesh with any one of the rows of teeth D⁴, D³, D², or D' then the motion of the shaft B is reversed and rotated at a corresponding rate of speed, according to which 95 of the concentric rows of teeth D⁴, D³, D², or D' the pinion E is moved in mesh with.

Having thus described my invention, I claim as new and desire to secure by Letters Patent—

1. A variable-speed and reversing gear, comprising a face-wheel having concentric rows of pins removably secured to the web of the wheel, means for holding the pins in place, and a pinion adapted to mesh with either of said rows of pins. 100

2. A variable-speed and reversing gear, comprising a face-wheel having concentric rows of pins removably secured to the web of the wheel, split rings engaging annular grooves in the pins and abutting against the under side 110 of the web of the wheel to hold the pins in place, and a pinion adapted to mesh with either of said rows of pins, on either side of the axis of the face-wheel.

3. A variable-speed and reversing gear, comprising a face-wheel having concentric rows of teeth each formed of pins removably secured on the web of the wheel, means for holding the pins in place, a shaft extending across the face of the wheel, and a pinion mounted to 120 turn with and to slide on the said shaft and adapted to mesh with either of said rows of teeth. 115

4. A variable-speed and reversing gear, comprising a face-wheel having concentric rows of spaced pins secured on the web of the wheel, means for removably holding the pins in place, a shaft extending across the face of the wheel, and a pinion mounted to turn with and to slide 125 on the said shaft and adapted to mesh with 130

either of said rows of pins on either side of the axis of the face-wheel.

5. A variable-speed and reversing gear, comprising a face-wheel having concentric rows of teeth on its face, a pinion adapted to mesh with either of said rows of teeth, the pinion consisting of a body or web, teeth movable in the body whereby they can be moved in or out of mesh with the teeth on the face-wheel, and a hub movable relative to the body and controlling the movement of the teeth.

6. A variable-speed and reversing gear, comprising a face-wheel having concentric rows of teeth on its face, a shaft extending across the face of the wheel, and a pinion adapted to mesh with either row of teeth on the face-wheel, the said pinion consisting of a hub mounted to slide on and to turn with the shaft, a web, and teeth mounted to slide radially in the web and controlled by the said hub.

7. A gear-wheel or pinion having a body, a hub slidable relative to the body, and radially-movable teeth controlled by the movement of the hub.

8. A gear-wheel or pinion, comprising a body, a hub slidable relative to the body and having an annular groove with beveled side walls, and teeth mounted to slide radially in the body and having tongues formed with beveled sides adapted to be engaged by the said side walls of the groove.

9. A gear-wheel or pinion comprising a web, a hub slidable relative to the web, and teeth mounted to slide radially in the said web, to project the teeth beyond the face of the said web or to withdraw the teeth within the web, the radial movement of the teeth being controlled by the said hub.

40 10. A gear-wheel or pinion comprising a web, a hub slidable relative to the web, teeth mounted to slide radially in the said web, to project the teeth beyond the face of the said web or to withdraw the teeth within the web, the radial movement of the teeth being controlled by the said hub, means for holding the said web against lengthwise movement, and

means for moving the said hub lengthwise relative to the said web.

11. A variable-speed and reversing gear, comprising a face-wheel having concentric rows of teeth on its face, each formed of a set of spaced pins, a shaft extending diametrically across the face of the said wheel and spaced from the terminals of the said pins, and a pinion mounted to slide on and to turn with the said shaft and adapted to mesh with either set of pins on either side of the axis of the face-wheel, the said pinion consisting of a hub mounted to slide on and to turn with the said shaft, a web, teeth mounted to slide radially in the said web and controlled by the said hub, means under the control of the operator for shifting the said pinion lengthwise on the said shaft, and means under the control of the operator for shifting the said hub lengthwise relative to the said web.

12. A variable-speed and reversing gear, comprising a face-wheel having concentric rows of teeth on its face, each formed of a set of spaced pins, a shaft extending diametrically across the face of the said wheel and spaced from the terminals of the said pins, and a pinion mounted to slide on and to turn with the said shaft and adapted to mesh with either set of pins on either side of the axis of the face-wheel, the said pinion consisting of a hub mounted to slide on and to turn with the said shaft, a web, teeth mounted to slide radially in the said web and controlled by the said hub, means under the control of the operator for shifting the said pinion lengthwise on the said shaft, and means under the control of the operator for shifting the said hub lengthwise relative to the said web, and locking devices for the said means.

In testimony whereof I have signed my name to this specification in the presence of two subscribing witnesses.
